COMBINATION KEY AND PERMUTATION
LOCK

Oscar V. Lalonde, Bronx, N. Y.

Application August 24, 1940, Serial No. 354,032

13 Claims. (Cl. 70—285)

This invention relates to improvements in locks and more particularly to improvements in locks combining key and permutation operating mechanism.

An object of the present invention is to provide a new lock mechanism wherein key operated parts and permutation operated parts have bolt actuating mechanisms substantially concentric.

Another object of the invention is to provide a lock mechanism in which a bolt operating part extends beyond the end of the casing to operate a bolt, such part being actuated either by key controlled mechanism or by permutation controlled mechanism.

Another object of the invention is to provide in a lock of the foregoing character concentrically arranged parts for cooperation with a bolt, such parts being respectively key and permutation controlled.

A further object of the invention is to provide new, simple and efficient permutation mechanism combined with a key operated lock of the tumbler pin type for alternative use.

A still further object of the invention is to provide a lock in which permutation mechanism is located for movement concentric with the core of the lock, which in turn has key operated mechanism eccentrically arranged therein, both the key operated mechanism and the permutation mechanism having concentric bolt operating portions.

Other features, objects, and advantages of the invention will be apparent by reference to the following detailed description of the accompanying drawings wherein—

Fig. 1 is a vertical section with parts in elevation of a lock embodying the invention;

Fig. 2 is a section taken substantially on line 2—2 of Fig. 1;

Fig. 3 is a collective view of the portions of the operating mechanism associated with the key and permutation controlled elements of the lock;

Fig. 4 is an end view of the lock shown in Fig. 1 illustrating the disposition of the permutation members thereon;

Fig. 5 is a section taken substantially on line 5—5 of Fig. 1;

Fig. 6 is a fragmentary perspective view of one of the selector rings used in the permutation mechanism;

Fig. 7 is a similar view of one of the adjustable permutation operating springs;

Fig. 8 is a perspective view of the trip used in the permutation mechanism;

Fig. 9 is a perspective view of the locking dog used in the same mechanism;

Fig. 10 is an enlarged fragmentary section taken substantially on the line 10—10 of Fig. 1; and

Fig. 11 is a collective view of parts of the invention in a modified form thereof.

Referring to the drawings and particularly to Figs. 1 to 5 inclusive, 10 indicates a metallic core member of the type commonly employed in locks utilizing pin tumbler arrangements. This core is of substantially cylindrical form for the main part thereof and has an eccentrically disposed counterbored through opening 11 therein for the reception of a flanged cylinder 12. The cylinder 12 has a keyway extending thereto and has a plurality of openings 14 in the periphery thereof and extending radially thereof for the reception of the usual pins 15. 15 The core 10 has a plurality of openings 16 aligned under certain conditions with the openings 14 and having complementary pins 17 therein normally forced toward the cylinder 12 by springs 18 retained in place by a keeper 19. This much 20 of the lock is a conventional form and requires no further illustration or description.

The core 10 has a plurality of peripheral grooves therein in which are frictionally seated split spring ring members 20, 21, and 22. These 30 rings are of similar construction being so formed that a relatively wide gap exists between the end parts thereof as shown in Fig. 6; the ring 23 thereof being shown in fragmentary form with a gap 24 between its end parts. Each of the rings 20, 21, and 22 has a groove 25 extending therearound and having a boundary flange so notched with oppositely disposed notches as to provide a plurality of upstanding shoulder parts 26. The space between adjacent 35 shoulder parts is of such width as to receive one of the fingers 27 extending from each side of the end of a spring member 28 which is wide enough to fit into the groove cut in the surface of a ring. The spring 28 shown in Fig. 7 is illustrated as having fingers 27 at each end thereof, but such spring 28 is utilized only on the ring 22 with other springs 28' on rings 20 and 24 having fingers 27' at one end thereof only. The purpose of these parts will be explained 40 later.

The core 10 has a recess 30 formed therein and extending from near the front end of the core the remainder of the full length thereof. The mouth of this recess 30 as shown in Fig. 5 is 45 of a width corresponding substantially to the

gap 24 between the ends of either of the rings 20, 21, or 22. A trip member 31 preferably formed from sheet metal is mounted in the recess 30. The lower edge of the trip member 31 is rolled into substantially a complete tube with extensions 32 and 34 at the ends thereof. A part of the trip 31 also has its edge portion rolled as at 35 and a tongue 36 is struck from the body of the member intermediate its ends. The trip is provided with a lever portion 37 near one end of the body part thereof. The extensions 32 and 34 are provided to mount the trip for limited rotary movement, the extension 34 fitting in a suitable opening in the front part of the core while the extension 32 fits in an opening in the bottom wall of a housing shell to be described later. A spring 38 has one end seated in a suitable enlargement in the bottom of the recess 30 while the other end engages the tongue 36 to normally force the trip 31 upwardly as shown in Fig. 5.

The permutation operating member comprises a sleeve 40 which fits around the core 10 making a snug fit with the flange 10' at the front end of this core. The forward end of the sleeve 40 is enlarged as at 41 with the inner surface thereof sloped outwardly as at 42 to provide a surface on which numerals (Fig. 4) can be located in a readily visible position. The opposite end of the sleeve 40 has an inwardly extending annular shoulder part or partition wall 44, the inner surface of which fits against a step cut in the periphery of the core 10. A tab or lug 45 is struck from the body of the shell adjacent the partition 44.

A gear ring 46 is positioned with one side thereof resting against a side of the partition 44 and with the inner edge thereof fitting in a cut-out part of the core 10. The ring 46 has a plurality of teeth 47 cut in the inner surface thereof and extending over a part of the length of the ring. As shown in Fig. 2, the ring 46 is not a complete ring but has its ends separated a distance sufficient to permit the mounting between these ends of a dog 48. One end of the dog 48 is rounded as at 49 to fit in a suitable recess in one end of the ring. A part of the dog is cut away to provide a recess 50 into which the upper end of the member 37 of trip 31 can extend. The upper surface of the dog 48 has substantially the same curvature as the ring 46 but is provided with an extension 51, one end of which is square as at 52 and the other end of which is sloped as at 53. An opening 49' in the wall of member 40 is of size to receive the extension 51 under certain conditions.

The parts previously described are held in assembly in the manner set forth and further by the aid of a shell member 55 which is of general cup shape and which is secured to the core by a screw 56 passing through the bottom of the cup member 55 into a threaded aperture in the core. This bottom also has apertures therein aligned with threaded apertures in the core for the reception of bolt members 57 utilized in securing the lock structure in place in a door or other support. The bottom also has an opening therein for the reception of the extension 32 of the trip 31 before mentioned.

The lock actuating mechanisms associated with this device are shown in Fig. 3. The cylinder 12 has the end thereof so shaped as to provide two substantially wedge shaped fingers 58 in diametrically opposite disposition. In connection with these fingers, use is made of a

blade member 59, the side edges of which are substantially stepped to have a part 60 of one width, a part 61 slightly wider, and an end part 62 still wider. The end part 62 is shaped in such fashion as to extend diametrically across the end of the cylinder 12 in contact with edges of the fingers 58. Also use is made of a gear member 64 which has a gear sector 65 in the periphery thereof and which has a through opening 66 with wedge shaped fingers 67 in diametrically opposite disposition extending into the opening. This opening 66 is of such dimensions that it can fit around the part 61 of the blade 59, and is of such diameter that the teeth 65 can engage the teeth 47 of the ring 46. Due to the increased width of a part 62 of blade 59 it follows that when the member 64 has been properly positioned on the blade, this part 62 cannot be withdrawn through the opening 66 of member 64. Thus, the parts can be assembled with the end part 62 of blade 59 in position against the end of cylinder 12 and then the member 64 positioned immediately against the end surfaces of the fingers 58. The excess of part 61 and the end part of the blade can extend through an opening in the bottom of the cup shell 55.

The operation and use of this lock mechanism are substantially as follows: With the parts assembled relative to the core, the permutation sleeve and the casing shell, such parts assume the relative position in Figs. 1, 2, and 5. Assuming that use is to be made of the key K for operating the lock, the key can be introduced into the cylinder 12 and this cylinder rotated in the fashion customary with locks employing pin tumblers as shown. When the cylinder 12 is rotated counter-clockwise, the members 58 bear against the end of the blade 59 and cause this blade to rotate with the cylinder as a unit. During this type of operation one or more of the rings 20, 21, and 22 have parts extending across the mouth of recess 30, thereby depressing trip 31, and consequently dog 48 through lever 37, so that gear member 64 and ring 46 can be moved along with the blade if required.

If the permutation part of the mechanism is to be used instead of the key, the sleeve 40 can be rotated first in one direction and then in another to set the parts associated therewith into such position that they can actuate the blade 59. For this reason, the rings 20, 21, and 22 fit in their respective grooves in the periphery of the core with sufficient friction to insure each ring remaining in any position, to which it is moved by the proper selective mechanism, after this mechanism has released contact therewith. For example, in one set-up of the permutation mechanism, the sleeve 40 is rotated counter-clockwise first so that tab or lug 45 picks up one of the fingers 27 on the spring 28 engaged with ring 22. This counterclockwise rotation is continued until one of the opposite fingers 27 on spring 28 engages a finger 27' on the spring associated with ring 21 and further until the opposite finger 27' on this same spring picks up finger 27' on the spring associated with the ring 20. The operator, knowing the combination necessary to operate this permutation mechanism, continues the counterclockwise rotation of the sleeve 40 until the first number of the combination has been reached (with the proper number of turns) at which time the gap 24 between the ends of the spring 28 will be in register with the mouth of recess 30 in the core. The sleeve 40 is then rotated clock-

wise causing the lug 45 to pick up the finger 21 on the opposite end of spring 28 and move it into engagement with a finger 27 associated with ring 21. Continued clockwise movement of the sleeve 40 through the proper number of turns to the second number of the combination brings the gap between the ends of ring 21 into register also with the mouth of recess 39. A second counter-clockwise movement of member 40 then causes the lug 45 to pick up finger 27 first engaged and continued movement in this direction to the third number of the combination brings the gap between the ends of the ring 22 also into alignment with the mouth of recess 39. When all three of the rings are so aligned, the spring 38 tends to force the trip 31 upwardly into the gaps between the ends of the rings and at the same time forces the dog 48 outwardly. If the slot or recess 49 in the end of the member 40 is aligned with the extension 54 of the dog, this extension is forced into the slot. However, under certain combination settings, these parts will not be in register but can be brought into register by clockwise movement of the member 40. This movement will be carried out slowly so that the dog can be forced into engagement with the slot. When such engagement takes place, further clockwise rotation of the member 40 causes movement of the dog and of the ring 46 in their channel and movement of the ring 46 in turn causes rotation of the member 64 due to the meshing of teeth 65 and 47. Rotation of the member 64 after an internal, brings the fingers 67 into contact with flat surfaces of blade 60 and this blade can be rotated along with the member 64 until it strikes the stationary members 58. The movement of the blade which can be accomplished is sufficient to operate a bolt or other mechanism associated with the lock. A counter-clockwise movement of the member 40 restores the parts to the Fig. 2 position so that when the member 64 is locked against movement, both by engagement with the gearless part thereof with the tapered inner surface of ring 46 and by clamping of the blade 59 between sets of members 58 and 67, further movement depresses the dog since one edge of the slot 49 can ride over the slope 53 on the dog extension. Such continued movement will cause the lug 45 to move the ring 22 to such an extent as to upset the established permutation or combination setting, requiring the operation of the parts in the manner before described to again effectuate operation of the permutation mechanism.

The purpose of having fingers 27 on each end of the spring 28 is to speed up the operation of the permutation mechanism since the alternate rotation of the member 40 to move the ring 22 requires approximately a half turn to cause engagement of fingers on the rings instead of a full turn which would be necessary if fingers were provided on only one end of the spring. Furthermore, while it has been specified that the springs associated with the rings 20 and 21 have fingers on only one end thereof, if desired, these springs likewise may have fingers at both ends. It will be evident that the combination setting of this mechanism can be varied at will by varying the positions of the fingers of the various springs relative to the ring with which they are associated since each ring has sufficient shoulders 26 to provide a large number of slots into which the fingers can be inserted. The arrangement wherein the blade 59 is retained in assembly by the respective fingers 58 and 67 makes possible rota-

tion of the blade either under the impetus of the cylinder 12 or under the impetus of the permutation mechanism through the agency of gear members 64. Even though the fingers 58 serve to limit rotation of the blade when the cylinder 12 is locked against movement by the complementary pin tumblers, still the blade can be rotated through a sufficient angle to effect desired bolt actuation. The blade actuating mechanisms before described are substantially concentric so that the blade can be operated by either thereof and, therefore, a minimum of parts are required for moving a bolt through these mechanisms.

In Fig. 11, a modified arrangement of bolt actuating mechanism has been shown. The arrangement is modified only in minor details and it is to be understood that the permutation mechanism is identical with that previously described. In Fig. 11, the key cylinder 112 is similar to cylinder 12 with the exception that the fingers 58 have been omitted and instead the rear end of the cylinder has been provided with an extension 114 of reduced diameter. The inner end of this portion 114 has flats 115 and is provided with an axial threaded aperture for the reception of a screw not shown. A gear member 164 has teeth thereon 165 similar to teeth 65. The member 164 has a bore of sufficient diameter to cause it to be rotatable about the extension 114. The member 164 also has a portion 167 of reduced diameter and this part 167 has flats 168 thereon.

These parts are assembled in a lock structure in the same manner as the parts 12 and 64 previously described and after the shell 55 has been secured in place by the screw 56, then the bolt actuating member 170 is introduced onto the end of the member 164 with the flats 171 of the aperture in the member 170 engaging the flats 168. The extension 114 of cylinder 112 is long enough to extend beyond the end of member 164 so that a second bolt actuating member 180 can fit on the end of the extension 114 with the flat walls 181 in the member 180 engaging the flats 115. A screw as before mentioned can be threaded into the aperture in the end of the extension 114 to hold these members 170 and 180 in assembly.

This type of mechanism is particularly useful in lock installations of the type known to the trade as "dead end locks" i. e., locks having bolts located in the door with operating mechanism available at one side only of the door. For purposes of illustration, a bolt 185 has been shown as having a long groove 186 cut in the under surface thereof and having a spring 187 surrounding a pin extension 188. This bolt consequently is spring operated to cause the tapered end 189 thereof to normally extend beyond the edge of a door.

When these parts are assembled with the mechanism previously described, the two members 170 and 180 extend into the slot 186 and in close proximity to the wall of this slot nearest spring 187. If the lock is key-operated, then rotation of cylinder 112 causes rotation of the member 180 so that the upper extension of this member 180 can move the bolt against the spring 187 to draw the bolt into the door. The slot 186 is long enough to accommodate the stationary member 170 during this operation. On the other hand, if the permutation controlled mechanism is used, then the member 170 is rotated, through the agency of gear 164, acting against the rear wall of the slot 186 in the same manner while the member 180 is stationary.

From the foregoing, it will be seen that the mechanism of the improved lock illustrated and

described herein possesses advantages not present in prior art devices. In either form of the mechanism, concentric parts are provided for moving a bolt, a switch, or any other desired movable member, and such parts can be operated either by key controlled mechanism or by permutation controlled mechanism. Thus, in either case, a minimum of parts extending beyond the confines of the lock assembly is necessary for efficient operation. It will be understood that modifications beyond the illustrated embodiments can be accomplished; in view of which any limitations imposed upon the invention are to be only those set forth in the following claims.

I claim:

1. In a lock of the type described, a key controlled rotary member for actuating bolt mechanism, and a permutation controlled rotary member for actuating the bolt mechanism, said rotary members being in substantially side-by-side relation and being substantially concentric, each of said rotary members being rotatable while the other is held against rotation.

2. In a lock of the type described, a housing, a key controlled rotary member extending outside said housing for actuating bolt mechanism, and a permutation controlled rotary member extending outside said housing for actuating the bolt mechanism, said rotary members being in substantially side-by-side relation and being substantially concentric, each of said rotary members being rotatable while the other is held against rotation.

3. In a lock of the type described, a bolt actuating blade, a key controlled rotary member for rotating said blade, and a permutation controlled rotary member for rotating said blade, said rotary members being in substantially side-by-side relation and being substantially concentric, each of said rotary members being rotatable while the other is held against rotation, and each serving as a stop to limit rotation of the blade under the impetus of the other rotary member.

4. In a lock of the type described, a bolt actuating blade, a key controlled cylinder for rotating said blade, and a permutation controlled rotary member for rotating said blade, said rotary member being substantially concentric to said cylinder in substantially side-by-side relation to the end thereof and having formations cooperating with formations on the blade to hold the blade in assembly with the rotary member and the cylinder.

5. In a lock of the type described, a housing shell, a bolt actuating blade extending beyond said shell, a key controlled cylinder in said shell for rotating said blade, said blade being connected to the inner end of said cylinder and a permutation controlled rotary member in said shell in substantially side-by-side relation with said inner end of the cylinder and connected to said blade for rotating the blade, said cylinder and said rotary member each being rotatable while the other is held against rotation.

6. In a lock of the type described, a core, a key controlled pin tumbler cylinder therein, permutation mechanism on the periphery of said core, bolt actuating mechanism in line with said cylinder and moved thereby, and bolt actuating mechanism connected to said permutation mechanism for operation thereby, said bolt actuating mechanisms being substantially concentrically arranged in substantially side-by-side relation.

7. In a lock of the type described, a housing shell, a core, a key controlled pin tumbler cylin-

der therein, permutation mechanism on the periphery of said core, bolt actuating mechanism extending beyond said shell in line with said cylinder and moved thereby, and bolt actuating mechanism extending beyond said shell and connected to said permutation mechanism for operation thereby, said bolt actuating mechanisms being substantially concentrically arranged in substantially side-by-side relation and being independently operable.

8. In a lock of the type described, a housing shell, a core, a key controlled pin tumbler cylinder therein, permutation mechanism on the periphery of said core, a bolt actuating member extending beyond said shell in line with said cylinder and moved thereby, and a connection between said bolt actuating member and said permutation mechanism whereby said member can be moved selectively by said cylinder and said permutation mechanism, said connection being disposed in substantially side-by-side relation with the end of said cylinder.

9. In a lock of the type described, a housing shell, a core, a key controlled pin tumbler cylinder therein and having one end extending beyond said shell, permutation mechanism on the periphery of said core, a bolt actuating member on the extending end of said cylinder, and a sleeve rotatable about the extending end of the cylinder, said sleeve being connected to said permutation mechanism for operation thereby, and a bolt actuating member secured to said sleeve adjacent the first mentioned bolt actuating member.

10. In a lock of the type described, a core, a key controlled cylinder therein, a plurality of spring rings rotatable in grooves spaced longitudinally of the periphery of said core, finger members selectively located in slots in said rings and having overlapping paths of movement, a tubular member surrounding said rings and having a formation adapted to engage a finger member of one of said rings to rotate all of said rings, a bolt actuating member at the end of said core and connected to said cylinder for movement thereby, means for connecting said bolt actuating member to said tubular member, and a trip, movable when the rings are in proper position, to operate said means whereby said bolt actuating member can be moved under the impetus of said tubular member.

11. In a lock of the type described, a core, a key controlled cylinder therein, a plurality of spring rings rotatable in grooves spaced longitudinally of the periphery of said core, finger members selectively located in slots in said rings, a tubular member surrounding said rings and having a formation adapted to engage a finger member of one of said rings to rotate said ring, a finger member of one ring being engageable with a finger member of an adjacent ring, a bolt actuating member at the end of said core, means to connect said bolt actuating member and said tubular member when the rings are in proper position, for causing movement of said bolt actuating member under the impetus of said tubular member, and means for independently moving said bolt actuating member under the impetus of said cylinder.

12. In a lock of the type described, a core, a key controlled cylinder therein, a bolt actuating blade connected to said cylinder for movement therewith, a plurality of spring rings rotatable in grooves spaced longitudinally of the periphery of said core, finger members selectively located in slots in said rings, a tubular member surround-

ing said rings and having a formation adapted to engage a finger member of one of said rings to rotate said ring, a finger member of one ring being engageable with a finger member of an adjacent ring, and means for connecting said tubular member to said blade when the rings are in proper position, for moving said blade under the impetus of said tubular member.

13. In a lock of the type described, a core, a key controlled cylinder therein, a bolt actuating member secured to the end of the cylinder, a plurality of spring rings rotatable in grooves spaced longitudinally of the periphery of said

core, engageable finger members, selectively located in slots in said rings, a tubular member surrounding said rings and having a formation adapted to engage a finger member of one of said rings, to rotate all of said rings, a second bolt actuating member concentric with the first bolt actuating member, and means for connecting said second bolt actuating member and said tubular member when the rings are in proper position, for causing movement of said second bolt actuating member under the impetus of said tubular member.

OSCAR V. LALONDE.
